UNITED STATES PATENT OFFICE.

EDWARD McMANEMIN, OF TIOGA, LOUISIANA.

WHEEL DRIVE.

Application filed April 28, 1924. Serial No. 709,577.

To all whom it may concern:

Be it known that I, EDWARD McMANEMIN, a citizen of the United States, residing at Tioga, in the parish of Rapides and State 5 of Louisiana, have invented certain new and useful Improvements in Wheel Drives; and I do hereby declare the following to be a full, clear, and exact description of the invention, such as will enable others skilled 10 in the art to which it appertains to make and use the same.

The present invention relates to improvements in wheel drives for vehicles and an object of the invention is to secure greater 15 traction and power without increasing the fuel consumption in the motor.

Another object of the invention is to provide a compact powerful drive suitable for tractors and other vehicles operating in soft 20 ground.

With the foregoing and other objects in view, the invention will be more fully described hereinafter, and will be more particularly pointed out in the claims appended 25 hereto.

In the drawings, wherein like symbols refer to like or corresponding parts throughout the several views,

Figure 1 is an end elevation showing the 30 improved drive construction in accordance with the present invention.

Figure 2 is a similar view taken from the opposite end of the drive and showing the shafts in section.

Figure 3 is a longitudinal vertical section taken on the line 3—3 in Figure 1.

Figure 4 is a longitudinal horizontal section taken on the line 4—4 in Figure 3.

Figure 5 is a central cross section taken 40 on the line 5—5 in Figure 3, and

Figure 6 is a transverse section taken on the line 6—6 also in Figure 3.

Referring more particularly to the drawings, 7 indicates the load shaft and 8 the power shaft. The load shaft is directly below and spaced from the power shaft and carries the weight of the vehicle; while the power shaft 8 is coupled to the motor by which it is rotated. Both shafts project into 50 a cylindrical casing 9. The outer end of the

casing 9 is closed by a head 10 having a threaded flange to engage with the threads, indicated at 11 on the outer side of the casing 10. The inner end of the casing 9 is also provided with screw threads 12 to receive 55 the threaded flange of the ring 13 which is provided with a circular opening and stepped shoulders 14 and 15, with which cooperate the similar shoulders 16 and 17 of the circular cover plate 18. 60

This cover plate fits within the circular opening of the ring 13, and is held in place by the latch ring 19 which overlaps the flange or shoulder 16 of the circular plate 18, and is removably secured to the ring 13. 65 as by the bolts 20. The closure plate 18 is provided with openings to fit about the shafts 7 and 8 and when the latch ring 19 is withdrawn, said plate 18 may be slid along the shafts to give access to the interior of 70 the casing 9.

The power shaft 8 is supported from the load shaft 7 and to this end two heart shaped plates 21 and 22 are fitted within the casing, the plate 21 being against the outer head 10, 75 while the plate 22 is fitted against the circular plate 18. The plates at their lower portions are provided with openings to snugly fit about the load shaft 7, the plates being supported by the load shafts and these heart shaped plates 21 and 22 do not come in contact with the bottom of the casing 9. At the upper ends the heart shaped plates are provided with bearings 23 and 24 to receive the power shaft 8 which rotates therein. The 80 power shaft is thus supported in the heart shaped plates 21 and 22, and the circular closure plate 18 is shown as being fitted rather loosely all around in order to permit the weight of the power shaft to devolve 90 upon the load shaft 7. The stepped shoulders of the closure plate 18 permit of this limited movement and at the same time exclude all foreign matter from the working parts on the interior of the casing 9. 95

The heart shaped plates 21 and 22 are connected together as by the rods or bolts 25 threaded as shown in Figure 4, in the threaded openings in the heart shaped plate 21 and having nuts 26 at their other ends 100

occupying sockets 27 in the opposite heart shaped plate 22, this latter plate being made of greater width to take the sockets and hold the nuts flush therein. Spacing sleeves 28 surround the rods 25 and serve to hold the plates 21 and 22 at a predetermined distance apart.

The power shaft 8 is provided with a pinion 29 within the central portion of the 10 casing having teeth adapted to engage in the interior notches 30 on the central part of the casing 9 by which rotary movement is communicated from the power shaft to the casing. The power shaft 8 is also provided with a collar 31 inwardly of, and abutting against the heart shaped plate 22 to prevent withdrawal of the power shaft.

The load shaft 7 extends within a sleeve 32 of larger internal diameter than the load 20 shaft as shown in Figure 5 and this interior sleeve 32 is in turn fitted within an external sleeve 33 of greater internal diameter than the exterior diameter of the internal sleeve 32. Both of these sleeves extends substantially the full distance between the plates 21 and 22 as shown in Figure 3 and they distribute the weight over wide surfaces, while also protecting the notched portion 30 in the intermediate part of the casing 9. By 30 having the sleeves larger than one another and larger than the diameter of the load shaft, the load is entirely free and adjusts itself automatically.

In the use of the device, the casing 9 may 35 be made of the same diameter as the usual wheel and a tire may be put upon it or not as desired; or this casing 9 may be made of the same diameter as the hub of an ordinary wheel and spokes, and rim and other 40 wheel parts added. The other parts of the device will of course vary in size according to the size of the casing 9. In either event the principle of the device will be the same, but where the casing itself is used as 45 the entire wheel, a large surface area will be exposed to the ground and a high traction afforded. The load 7 will be entirely supported upon the lower portion of the casing and the power shaft 8 will be free so 50 that there will be no binding of the teeth of the pinion 29 in the notches of the casing 9. A considerable reduction in gearing is had and with the load supported as indicated great power will be secured. By 55 virtue of the construction of the various parts the interior of the casing is readily accessible and parts may be removed and replaced without great difficulty and delay.

It will be understood, of course, that the 60 wheel 29, instead of having teeth may be a friction wheel. Also if a rope is wound about the drum 9 and this rope is pulled motion may be communicated to the shaft 8 and the wheels in this case if on the shaft

motion may be communicated to the 65 vehicle.

It is obvious that various changes and modifications may be made in the details of construction and design of the above specifically described embodiment of this 70 invention without departing from the spirit thereof, such changes and modifications being restricted only by the scope of the following claims.

What is claimed is:—

1. A wheel drive for vehicles comprising load and power shafts, a casing enveloping the end portions of the shafts, means whereby said power shaft may have driving connection with the casing, plates for supporting the power shaft from the load shaft, and elongated sleeves extending about the load shaft and resting upon the lower portion of the casing.

2. A wheel drive for vehicles comprising a power and a load shaft extending in spaced relation with the load shaft lowermost, a casing extending about the end portions of said shafts and having notches therein, a gear wheel on said power shaft meshing with the notches to drive the casing, sleeves fitted about the load shaft and resting upon the lower portion of the casing, means to support the power shaft and gear wheel from the load shaft, and means for enclosing the ends of the casing.

3. A wheel drive for vehicles comprising a power shaft, a load shaft spaced below the power shaft, a pinion fixed to the power shaft, a casing enveloping end portions of said shafts and having notches for driving engagement with said pinion, a pair of heart shaped plates carried by the load shaft within the casing and having bearings for said power shaft, elongated sleeves extending about the load shaft between said plates and resting upon the lower side of the casing, and covers for enclosing the ends of said casing.

4. A wheel drive for vehicles comprising power and load shafts, a casing extending about the end portions of said shafts, a pinion on the power shaft for driving engagement with said casing, a pair of heart shaped plates in said casing supported by said load shaft and having bearings to receive the power shaft, connecting rods for said heart shaped plates, means associated with the rods to keep the plates spaced apart, and elongated concentric sleeves extending loosely within one another and loosely about said load shaft and resting upon the bottom portion of the casing, and means to enclose the ends of said casing.

5. A wheel drive for vehicles comprising a power shaft and a load shaft, a casing partially enveloping said shafts, an inner sleeve loosely fitted to said load shaft, an

outer sleeve loosely fitted about the inner sleeve and resting upon the bottom of said casing, a pair of plates for confining the ends of said sleeves, said plates being carried by the load shaft and supporting for rotary movement the power shaft, a gear element carried by said power shaft and having driving connection with said casing, means for holding said plates apart, an out-

er end head removably connected to said casing, a ring having a circular opening with stepped shoulders fitted on the inner end of the casing, a closure plate also having stepped shoulders loosely fitting the stepped shoulders of the ring, and a latch ring removably secured to the first named ring and overlapping the edge of said plate.

EDWARD McMANEMIN.
